CLAIM

Related U.S. Application Data

The ornamental design for a combined diverter and
separator unit for an oil storage tank, as shown and
described.

[60] Division of Ser. No. 575,048, Jan. 30, 1984, abandoned,
which is a continuation-in-part of Ser. No. 431,150,
Sep. 30, 1982, abandoned.

DESCRIPTION

[52] U.S. Cl. D23/206; D23/207
[58] Field of Search D15/7, 9; D23/3, 4;
55/36, 41-42, 171-172, 192-193, 482, 529;
D12/194

FIG. 1 is a top, front perspective view of a combined
diverter and separator unit for an oil storage tank show-
ing my new design;

FIG. 2 is an enlarged top plan view thereof;

FIG. 3 is an enlarged bottom plan view thereof;
FIG. 4 is a side elevational view thereof, the side oppo-
site being identical in appearance; and

FIG. 5 is a front elevational view thereof, the rear being
identical in appearance.
